UNITED STATES PATENT OFFICE.

LOUIS J. BARRY, OF NEWPORT, RHODE ISLAND.

TORPEDO.

Application filed March 17, 1924. Serial No. 700,195.

This invention relates to improvements in torpedoes and more particularly to the depth regulating mechanism.

As is well-known to those familiar with the art, torpedoes are provided with means for controlling the horizontal rudders for maintaining substantially uniform depth throughout the run. This mechanism is usually actuated by hydrostatic pressure of the water upon a suitable diaphragm which is connected by intervening mechanism with the horizontal rudder. It is also customary to provide means for regulating the depth.

Owing, however, to the exceedingly high temperatures in the after-body of the torpedo which causes more or less expansion and contraction of the various parts, the depth regulating mechanism is not always uniform throughout the entire run and it is, therefore, one of the objects of the present invention to provide a more reliable and efficient mechanism for maintaining uniform depth.

A further object is to provide a simple and practical mechanism which will be water-cooled thereby avoiding some of the above objections.

A further object is to provide an improved setting mechanism for the depth gear whereby the same may be easily and quickly operated.

A further object is to provide a mechanism of the above character which may be installed in torpedoes now in use without material alteration of the mechanisms or parts now contained therein.

Other objects will be in part obvious and in part hereinafter pointed out in connection with the accompanying sheets of drawings forming a part of the present disclosure and in which drawings corresponding parts are denoted by similar reference characters.

In these drawings, Figure 1 is a diagrammatic view of the after-body of a torpedo showing the relative location of the depth control mechanism and the setting mechanism therefor.

Figure 2 is a partial sectional plan view of the depth control mechanism.

Figure 3 is a sectional view taken substantially along the line 3/3, Figure 2.

Figure 4 is a sectional view taken substantially at right angles to Figure 3, certain parts being omitted for the sake of clearness.

Referring now to the drawings in detail, 5 denotes the shell of the after-body of the torpedo in the upper part of which is provided an indicator and setting mechanism 6 which connects through gears 7 to a vertical shaft 8 which is provided at its lower end with a beveled gear 10 meshing with a second gear 11 on a shaft 12, the opposite end of which is secured in a nut 13. The end of this shaft 12 is threaded at 14 and provided with a collar 15 carrying a screw 16 sliding in a groove 17. Thus as the shaft 8 is rotated the shaft 14 will be rotated a corresponding amount to move the collar 15 along the slide and control the tension of a spring 18 mounted upon a shaft 14 and reacting against a pivot yoke 20.

One arm of this yoke is adapted to be engaged by diaphragm plate 21 on the upper part of which is a flexible diaphragm 22 that is clamped about its periphery as indicated.

This diaphragm 22 together with a circular cup-shaped member 23 provides an air chamber 24 which is adapted to be completely surrounded by water which may enter through the opening 25 and passages 26 whereby this chamber is cooled at all times by the water in which the torpedo is immersed. The shaft 12 is provided with a worm 27 coacting with a pinion 28 which constitutes a dial or indicating mechanism visible through an opening 30. This pinion 28 is moved proportionally to the setting mechanism 6. To the upper part of the diaphragm plate 21 is attached a shaft 31 which connects through a bell crank lever 32 connected with the steering engine to a pull rod 33 extending aft in the torpedo for controlling the horizontal rudder.

The air chamber 24 is adapted to be fastened to the present gyro base and a diaphragm plate 21 acts against the leverage 31, 32 and 33 as above described. The tension of the spring 18 is varied by turning the adjusting screw or setting mechanism 6 through the gears 10 and 11 and the dial will indicate the setting of the spring and check up the regular setting dial on the top of the 105 torpedo as indicated at 6.

It will thus be seen that when the torpedo is launched the water entering through the port 25 and passages 26 will act upon the diaphragm 22 and move the same downwardly against the tension of the spring 18. As the hydrostatic pressure changes with

changes in the depth of the torpedo the diaphragm moves up and down and accordingly reacts upon the horizontal rudder whereby the torpedo is maintained at a substantial uniform depth.

It will thus be seen that the present invention provides a simple and practical depth control mechanism for torpedoes which will be substantially uniform in its operation due to the cooling action of the water in which the torpedo is traveling.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and, therefore, such adaptations should and are intended to be comprehended within the meaning and range of equivalency of the following claims.

What I claim is:

- 25 1. In a torpedo, in combination, a diaphragm for closing one side of an air chamber of which a second side is in metallic contact with the shell of the torpedo, means connecting said diaphragm with the horizontal rudder and means whereby said air chamber is completely surrounded by the water in which the torpedo travels.
- 30 2. In a torpedo, in combination, a member constituting an air chamber one side of which is in metallic contact with the shell of the torpedo, a flexible diaphragm associated therewith, intermediate mechanism between the diaphragm and the horizontal rudder, a spring adapted to resist movement of the diaphragm, means for adjusting the tension of said spring and passages completely sur-

rounding said air chamber to permit the circulation of cooling fluid.

3. In a torpedo, in combination, a member constituting an air chamber one side of which is in metallic contact with the shell of the torpedo, a flexible diaphragm associated therewith, intermediate mechanism between the diaphragm and the horizontal rudder, a spring adapted to resist movement of the diaphragm, means for adjusting the tension of said spring and passages surrounding said air chamber to permit the circulation of cooling fluid, said passages being open to the water in which the torpedo travels.

4. In a torpedo, in combination, a member constituting an air chamber, a flexible diaphragm forming one side thereof, intervening mechanism between the diaphragm and the horizontal rudder, depth setting mechanism including a spring acting against the movement of the diaphragm, said air chamber being included in but spaced from the after-body of the torpedo to permit circulation of the cooling medium completely there-around.

5. In a torpedo, in combination, a member constituting an air chamber, a flexible diaphragm forming one side thereof, intervening mechanism between the diaphragm and the horizontal rudder, depth setting mechanism including a spring acting against the movement of the diaphragm, said air chamber being included in but spaced from the after-body of the torpedo to permit circulation of the cooling medium completely there-around and means for setting the depth at which the torpedo is adapted to travel from the upper side of said torpedo.

Signed at Newport, Rhode Island, this 28th day of July, 1923.

LOUIS J. BARRY.
